United States Patent Office

Des. 212,522
Patented Oct. 29, 1968

212,522

ELASTIC FABRIC BAND

Robert T. Spillane, Wernersville, Pa., assignor to Wyoming Corporation, Reading, Pa., a corporation of Pennsylvania

Filed July 10, 1967, Ser. No. 7,746

Term of patent 14 years

(Cl. D3—33)

FIG. 1.

FIG. 2.

FIG. 3.

FIG. 1 is a face view of an elastic fabric band embodying my design;

FIG. 2 is a back view of the band shown in FIG. 1; and

FIG. 3 is a sectional view taken on the line 3—3 of FIG. 1.

I claim:

The ornamental design for an elastic fabric band, substantially as shown.
